UNITED STATES PATENT OFFICE

BENJAMIN GILOWITZ, OF NEW YORK, N. Y., ASSIGNOR OF ONE-EIGHTH TO JOSEPH SMITH AND TWENTY PERCENT TO EMANUEL S. STEINBERG, BOTH OF BRONX, NEW YORK, N. Y.

COMPOSITE SHOE HEEL SHEET

Original application filed August 29, 1929, Serial No. 389,236. Divided and this application filed January 31, 1930. Serial No. 424,935.

The invention aims to provide for the manufacture and marketing of a plurality of novel shoe heels, heel lifts or other shoe treads carried by a single flexible sheet of 5 rubber or the like and adapted to be cut from said sheet as needed without danger of impairing their shape.

With the foregoing in view, the invention resides in the novel subject matter herein- 10 after described and claimed, description being accomplished by reference to the accompanying drawings.

Figs. 1 and 2 are elevations showing the opposite sides of an article of manufacture 15 constructed in accordance with the invention.

Fig. 3 is a sectional perspective view on line 3—3 of Fig. 1.

The unique article of manufacture em- 20 bodies a flat sheet 32 of rubber or the like, and two sets of resilient tread members 33—34 joined to opposite sides of said sheet respectively. Preferably, the tread members 33 are moulded integrally with the sheet 32 25 whereas the members 34 are formed separately from said sheet and cemented or vulcanized thereto. Both sets of the members 33—34 are heel-shaped in the present disclosure and any one of the members 33 is di- 30 rectly opposite and of the same size and shape as one of the members 34. Thus, by cutting the sheet 32 around the edges of the opposed members 33—34, a complete heel or a heel lift may be provided, according to the size in 35 which the article is manufactured. The members 34 are each formed with a central rather large opening 35, these openings ex- 40 tending from the upper to the lower sides of said members and being occupied by wear resisting inserts 36 which are vulcanized, ce- 45 mented or otherwise tightly secured in the openings and against the sheet 32.

By using the heel or lift just described with the member 33 downwardly, the appear- 45 ance is given of an all rubber heel or lift. When desired however, the devices may be applied in an inverted position with the inserts 36 exposed downwardly to assist in re- 50 sisting wear. These inserts form effective anchorage for the attaching nail heads, re-

gardless of which side of the device is secured against the heel body. By having the members 33 and 34 at opposite sides of the sheet 32, cutting of the latter will not endanger the true shape of the heel at either 55 its upper or lower portion, and any portion of the sheet 32 left projecting from the heel, can easily be ground off or otherwise removed after attaching the heel to the shoe.

The formations 37 as seen more particu- 60 larly in Fig. 2, are simply small webs connecting the tread members 33 and formed by the rubber filling ports which connect the various mould recesses in which said members 33 65 are formed.

By the novel construction shown and de- 70 scribed, a very advantageous and salable article is provided, yet one which may be easily and inexpensively manufactured.

This application is a division of my parent 70 U. S. application, Serial No. 389,236, filed August 29, 1929.

I claim:

1. In the shoe heel art, an article of man- 75 ufacture comprising a flexible sheet, upper and lower sets of resilient shoe tread members joined to the upper and lower sides of said sheet, and wear resisting inserts inset in one set of said tread members, any of said tread members at either side of the sheet being di- 80 rectly opposite one at the other side and being of the same size and shape as the latter.

2. In the shoe heel art, an article of man- 85 ufacture comprising a flexible sheet, resilient shoe tread members joined to one side of said sheet, additional resilient shoe tread mem- 90 bers joined to the other side of said sheet, each of said additional members having a central cut-out from one of its sides to the other, and flat wear-resisting inserts within said 95 cut-outs and secured against said sheet, any of said tread members at either side of the sheet being directly opposite one at the other side and being of the same size and shape as the latter.

In testimony whereof I have hereunto af- 100 fixed my signature.

BENJAMIN GILOWITZ.
